UNITED STATES PATENT OFFICE

119,281

DESIGN FOR A COMBINED TISSUE DISPENSER AND VANITY CHEST

Paul P. Paisner, Chicago, Ill.

Application October 20, 1939, Serial No. 87,747

Term of patent 3½ years

To all whom it may concern:

Be it known that I, Paul P. Paisner, a citizen of the United States, residing at Chicago, in the county of Cook and State of Illinois, have invented a new, original, and ornamental Design for a Combined Tissue Dispenser and Vanity Chest, of which the following is a specification, reference being had to the accompanying drawings, forming part thereof.

Fig. 1 is a perspective view and Figs. 2, 3 and 4 are side elevational, plan and front elevational views, respectively, of a combined tissue dispenser and vanity chest, showing my design.

I claim:

The ornamental design for a combined tissue dispenser and vanity chest, as shown.

PAUL P. PAISNER.
